UNITED STATES PATENT OFFICE.

CHARLES C. TOMKINSON, OF PLAINFIELD, NEW JERSEY, ASSIGNEE TO J. EDWARD OGDEN, OF MOUNTAINVILLE, NEW YORK.

EXPANSION SHIELD.

Application filed December 20, 1922. Serial No. 607,966.

This invention relates to expansion shields employed for obtaining anchorage in walls of brick or stone or cementitious material not adapted to directly receive a threaded 5 element or bolt.

This invention has for its object to provide a shield having superior gripping qualities and a shield that will gradually increase its gripping effect as the expanding element 10 advances therein.

Another object of the invention is to provide a shield of the character described that is simple in construction and can be economically manufactured.

15 Further objects of the invention will appear from the following specification taken in connection with the drawings, which form a part of this application, and in which

Fig. 1 is an elevational view of an expansion shield constructed in accordance with the invention.

Fig. 2 is an elevational view taken at right angles to Fig. 1.

Fig. 3 is a transverse sectional elevation 25 taken substantially on line 3-3 of Fig. 1.

Fig. 4 is an elevational view of the inner end of the shield shown in Fig. 2.

Fig. 5 is a transverse sectional elevation taken substantially on line 5-5 of Fig. 4.

30 Fig. 6 is a sectional elevation similar to Fig. 5 but showing the shield partially expanded in a wall opening.

Fig. 7 is an elevational view of the shield showing the excess metal before it is folded 35 back on the outer surface of the shield.

Fig. 8 is a detail elevational view showing a strip of excess metal used in connection with the shield shown in Figs. 1 to 6 and preferably welded thereon.

40 Fig. 9 is an elevational view similar to Fig. 1 but illustrating another form of the invention.

Fig. 10 is an elevational view taken at right angles to Fig. 9.

45 Fig. 11 is an elevational view of the inner end of the shield shown in Figs. 9 and 10.

Fig. 12 is a view half in section and half in elevation illustrating another form of the invention, and

50 Fig. 13 is a sectional elevation illustrating a still further form of the invention.

The invention briefly described consists of an expansion shield having superimposed on its outer surface and connected thereto excess metal tapered in width longitudinally 55

of the shield and having its greatest cross sectional dimension at the inner end of the shield, this dimension gradually decreasing toward the outer end of the shield. This excess metal may be formed integral with the 60 shield or may be secured thereto in any suitable manner as by welding and, if desired, a plurality of excess metal layers may be used. As the expanding element advances into the shield from the outer toward the inner end 65 thereof, the excess metal is forced outwardly into engagement with the bore of the opening, and from the proportions of the superimposed metal it will be evident that a small area will be initially forced outwardly and 70 that this area will increase as the expanding element advances. Further details of the invention will be clear from the following description.

The expansion shield may be of any desired shape or form and in the embodiment of the invention shown the shield comprises a pair of sections 20 and 21, one of the sections having tabs 22 engaging the other section and retaining the sections together. 75

The two sections are tapered longitudinally as shown particularly in Fig. 2 to form a constricted bore decreasing in width from the outer to the inner end of the shield on an axis at right angles to the line of division 80 between the sections. The two sections are corrugated longitudinally, the corrugations registering to form a screw thread for receiving a lag screw 23.

Each section has superimposed on the 85 tapered portion of its outer surface and intermediate the longitudinal edges thereof excess metal and in the form of the invention shown in Figs. 1 to 7 inclusive this excess metal is formed by a substantially triangular 90 extension 24 of the shield material, this portion 24 extending beyond the inner end of the shield. The extension 24 is bent backwardly onto the outer surface of the shield as shown in Figs. 1, 2, 5 and 6 with the apex 95 of the triangle extending toward the outer end of the shield. The excess metal extension or strip 24 is transversely corrugated in a manner similar to the shield sections and is shown as beveled at 25. 100

In the form of the invention shown in Figs. 1 to 8 inclusive an additional piece of excess metal is superimposed upon each extension 24, this additional piece 26 being 105 preferably secured to the extension 24 by 110

welding. The piece 26 is also preferably triangular with the apex extending toward the outer end of the shield.

From the showing in Figs. 1, 2 and 5 it will be noted that the outer portions of the shield and excess metal lie in substantially a single cylindrical surface.

In the form of the invention shown in Figs. 9 and 10, the excess metal strip 30 is also tapered in width, being substantially triangular in outline but is also corrugated longitudinally as shown at 31 in Fig. 11. The outer end of the shield illustrated in Figs. 9 and 10 is flared at 32 to increase the diameter of this end a sufficient extent to cause the outer periphery of the outer end of the shield to lie in a cylinder including in its surface also the outer surfaces of the corrugations 31 of the excess metal 30. In the form of the invention shown in Figs. 9 and 10, the excess metal 30 may be secured to the shield in any desired manner.

A modification of the construction shown in Figs. 9 to 11 is illustrated in Fig. 12 and in this form of the invention the excess metal 40 is formed from separate material and is secured to the shield by means of tabs 41 which are bent around the edges of the shield sections. The shield sections are bent back at their ends providing end portions 42 which close the inner ends of the corrugations, thereby preventing cement or wall material from entering the corrugations of the strip 40.

In Fig. 13 the excess metal 50 is made thicker at its apex than the remaining portions thereof and, therefore, as this shield is inserted in the opening, it must be driven therein by force and withdrawal thereof from the opening is prevented by the wedging action of the end of the excess metal 50.

In use the shields shown in Figs. 1 to 12 inclusive are inserted in a wall opening and expanding means such as a lag screw is inserted in the shield. As this screw advances in the shield more and more excess metal will be forced into engagement with the bore of the opening, the engaging area increasing gradually, thereby also increasing the gripping effect of the shield. This action is also true of the construction shown in Fig. 13 but as above stated the shield illustrated in Fig. 13 must be initially forced into the opening unless the opening is of sufficient dimension to receive the outwardly extending end portions of the excess metal 50.

Although certain specific embodiments of the invention have been shown and described, it will be understood that the invention is capable of modification and that further changes in the construction and in the arrangement of the various cooperating parts may be made without departing from

the spirit or scope of the invention as expressed in the following claims.

65

What I claim is:

1. An expansion shield comprising a pair of expandable sections forming a tubular member constricted to form a bore varying from a circle to an oval in cross section from end to end, the shorter axis of the oval being disposed substantially at right angles to the plane of division of the shield sections, and excess metal secured to the outer surfaces of said sections intermediate and spaced from the longitudinal edges thereof.

70

2. An expansion shield comprising a pair of expandable sections forming a tubular member constricted to form a bore varying from a circle to an oval in cross section from end to end, the shorter axis of the oval being disposed substantially at right angles to the plane of division of the shield sections, and excess metal secured to the outer surfaces of said sections intermediate and spaced from the longitudinal edges thereof, said excess metal increasing in cross sectional dimension from the outer to the inner end of the shield.

75

3. An expansion shield comprising a pair of expandable sections forming a tubular member constricted to form a bore varying from a circle to an oval in cross section from end to end, the shorter axis of the oval being disposed substantially at right angles to the plane of division of the shield sections, and excess metal secured to the outer surfaces of said sections intermediate and spaced from the longitudinal edges thereof, said excess metal increasing in cross sectional dimension from the outer to the inner end of the shield and having its greatest cross sectional dimension at the most constricted portion of the shield.

80

4. An expansion shield comprising a pair of sections, each section having secured to its outer surface intermediate and spaced from the longitudinal edges thereof a plurality of layers of excess metal.

85

5. An expansion shield comprising a pair of sections, each section having secured to its outer surface, intermediate and spaced from the longitudinal edges thereof, a plurality of layers of excess metal, said layers decreasing in width from the inner toward the outer end of the shield.

90

6. An expansion shield comprising a pair of sections, each section having secured to its outer surface, intermediate the longitudinal edges thereof, a plurality of layers of excess metal, certain of said layers being formed integral with the sections and others welded thereto.

105

In witness whereof, I have hereunto set my hand this 16th day of December, 1922.

CHARLES C. TOMKINSON.
